UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

METHOD AND APPARATUS FOR MAKING INGOT-MOLD FEEDERS.

Application filed December 29, 1923. Serial No. 688,504.

To all whom it may concern:

Be it known that BLOOMFIELD H. HOWARD and ERNEST J. TURNER, citizens of the United States, residing, respectively, at Washington, District of Columbia, and Pittsburgh, in the county of Allegheny and State of Pennsylvania, have invented certain new and useful Improvements in Methods and Apparatus for Making Ingot-Mold Feeders, of which the following is a specification.

Our invention relates to improvements in method and apparatus for making sectional ingot mold feeders.

15 The object of our invention is to provide a method and means whereby a section or sections of an ingot mold feeder may be formed of plastic material by forcing it through a die having a passage corresponding to the section of the feeder.

Another object of our invention is to provide a method and die for making ingot mold feeders in which the sections when formed singly or in multiple will have the 20 contour of a perfect feeder when the predetermined number of sections are assembled.

A further object of our invention is to provide a die in which the ends are made so as to form the sections of the feeder with the interlocking faces.

25 A still further object of our invention is to provide a method and a die of this character which is simple in construction and operation and having certain details of structure and combination of parts herein-after more fully set forth.

In the accompanying drawings:

Figure 1 is a vertical sectional view of 30 a cylinder and plunger showing our improved die carried by the lower end.

Figure 2 is a bottom plan view looking in the direction of the arrow of Figure 1 showing the die having a number of passages for simultaneously making sections to form a complete feeder when assembled.

Figure 3 is a similar view to Figure 2 showing the die having two passages for making a two section ingot mold feeder.

35 Figure 4 is a view similar to Figure 2 showing a four passage die for forming a fluted ingot mold feeder.

Figure 5 is a view similar to Figure 2 showing a die to form a square feeder each 40 die forming one side of the feeder whereby

the joint of the several sections are arranged at the corner of the square feeder.

Figure 6 is an enlarged plan view of four die sections secured together and showing the plungers for compressing plastic material 60 in each section to form a circular ingot mold feeder.

Figure 7 is a plan view of a modified form of die.

Figure 8 is a cross sectional view taken 65 on line 8—8 of Figure 7.

Figure 9 is a plan view of a still modified form of die and forming one of the sections of an ingot mold feeder.

Figure 10 is a plan view of a portion of 70 the die showing a V-shaped partition for forming the ends of the sections with interlocking edges.

Figure 11 is a plan view similar to Figure 10 showing a curved partition for forming the ends of the sections with interlocking edges.

Referring now to the drawings 1 represents the cylinder in which is arranged a plunger 2 for compressing the refractory 80 material in the cylinder and forcing it through the die as will be hereinafter more fully described. The refractory material is fed into the cylinder below the plunger in any desired manner. The lower end of the 85 cylinder has bolted thereto a section 3 carrying a spreader 4 which is adapted to spread and break up the refractory material before its passage to the die. Carried by the lower end of the section 3 is a section 5 which has 90 at its lower end, an annular outwardly extending flange 6 to which is bolted a die section 7 by means of the bolts 8. This die section has its inner periphery beveled as indicated at 9. The spreader 4 has a downwardly extending cylinder member 10, internally screw-threaded and into which is 95 screwed the bolt 11 which clamps the die member 12 thereto. This die member on its outer periphery is beveled as indicated at 100 13 and whereby the passages 14, 15, 16 and 17 are flared outwardly so as to cause a compression of the plastic material in the lower end of the passage. The inner and outer die members 7 and 12 are connected at proper 105 intervals with vertical partitions 18, 19, 20 and 21 which form the four passages 14, 15, 16 and 17. These partitions extend from the upper end of the die members to the lower end.

By this construction it will be seen that the plunger 2 is forced downwardly into the cylinder forcing the refractory material into the upper flared ends of the passages 14, 15, 16 and 17 and is forced therethrough forming four separate feeder sections. The sections are supported upon the table 22 which is supported by the rod 23. This rod is moved upwardly and is retracted when the sections are being formed in the die so that when the feeder section or sections of sufficient length have been formed, the plunger or piston 2 is stopped and the table 22 is also stopped while the sections are cut off in any desired manner at a point close to the lower ends of the dies.

In the modification shown in Figure 3 of the drawings only two partitions 24 and 25 are provided therein making two passages 26 and 27 whereby a two section feeder is formed.

In Figure 4 we have shown the dies of a fluted form as indicated at 28 and showing three partitions 29, 30 and 31 whereby a three section feeder is formed.

In Figure 5 we have shown a square die having the partitions 31, 32, 33 and 34 arranged at the corners so that each section 30 of the feeder is practically one side of the feeder.

In Figure 6 instead of making the die in one piece we have shown it made in four sections 35, 36, 37 and 38 which may be secured together in any desired manner or may be used separately to form a single section in which event a plunger 39 is arranged in a receptacle above the die section which operates through a rod 40. By this structure 40 it will be seen that we are able to make the sections singly or in a series of 1, 2, 3 and 4 or more. The same principle could be applied to the form shown in Figure 1. Instead of having the die of a single piece 45 and having the partition integral, the die sections could be made as shown in Figure 6 and the single plunger used to force the refractory material out through the four passages forming the four feeder sections.

Having thus fully described our invention what we claim is:—

1. A method of forming sectional ingot mold feeders comprising a die and means for forcing plastic material through the die 55 forming a section a number of which are adapted to form a complete ingot mold feeder.

2. A method of forming ingot mold feeders consisting of forcing plastic material through dies having openings therein to 60 form a number of sections which when assembled form a complete feeder, the abutting faces of which form a tight joint.

3. A method of forming ingot mold feeders consisting of forcing plastic material 65 through dies having openings therein to form a number of sections which when assembled form a complete feeder, the abutting faces of which form an interlocking joint.

4. A die for forming ingot mold feeders comprising a member having a passage therethrough provided with vertical partitions whereby refractory material is forced through the passage between the partitions 75 forming several sections to form a complete feeder when assembled.

5. A die for ingot mold feeders comprising a plate having a continuous passage therethrough provided with partitions to 80 form several sections through which the plastic material is forced and said passage of a shape to form a complete ingot mold feeder.

6. A die for making ingot mold feeders 85 comprising a plate having passages therethrough forming sections, said passages of a shape to form a complete ingot mold feeder.

7. A die for making ingot mold feeders comprising a plate having a series of passages therethrough, each passage forming 90 one portion of an ingot mold feeder.

8. A die for making ingot mold feeders comprising a series of passages therethrough and having flared upper ends, said passages 95 of the same area as the completed ingot mold feeder.

9. A die for making ingot mold feeders comprising a series of sections secured together and each section having a passage 100 therethrough and means for forcing the plastic material through the several sections.

10. A die for making ingot mold feeders comprising a plate having a passage therethrough and flared upper ends, partitions 105 dividing the passage into a number of smaller passages and means for forcing the plastic material through the die and whereby several sections are formed which when combined, form a complete feeder.

In testimony whereof we affix our signatures.

BLOOMFIELD H. HOWARD.
ERNEST J. TURNER.
